UNITED STATES PATENT OFFICE

ROY SELDEN SANFORD, OF SOUTH BEND, INDIANA, ASSIGNOR TO BENDIX BRAKE COMPANY, OF SOUTH BEND, INDIANA, A CORPORATION OF ILLINOIS

BRAKE MECHANISM

Application filed March 20, 1929. Serial No. 348,515.

My invention relates to improvements in brake mechanism and particularly to brakes for the road wheels of motor vehicles.

More specifically the invention resides in a brake mechanism provided with an improved servo responsive to the rotation of the brake drum, improved means for actuating the servo into engagement with the drum and improved operating connections between the servo and the remaining brake mechanism for urging the same into braking engagement with the drum.

An object is the provision, in brake mechanism of the character set forth and having a rotatable brake drum, of retarding means arranged to be moved into frictional engagement therewith and a servo shoe disposed within said retarding means and adapted to be independently moved into engagement with the drum, said servo shoe being coupled with the retarding means to urge it into frictional engagement with the drum.

The retarding means preferably embodies a plurality of brake shoes and a servo shoe disposed entirely within one of them. The shoe within which the servo shoe is arranged is here shown as a floating brake shoe pivotally articulated with a second brake shoe to apply both brake shoes to the drum.

Power multiplying connections couple the servo shoe with the brake shoes to brake them into engagement with the drum in either direction of drum rotation. The servo shoe and the brake shoes are constrained away from the drum by suitable springs and adjustable devices are provided to determine the retracted positions of such shoes.

The servo shoe is supported to swing from one end by linkage which embodies in part operating means for urging the brake shoes for engagement with the drum and the servo shoe is automatically angularly adjustable upon this linkage to vary its normal position with respect to the drum to take up for wear.

Other objects and meritorious advantages of my invention will more fully appear from the following description of the illustrative embodiment shown in the accompanying drawing and defined in the appended claims.

In the drawing:

Fig. 1 is a vertical sectional view through a brake drum and brake mechanism embodying my invention.

Fig. 2 is a fragmentary plan of a portion of the brake mechanism.

Fig. 3 is a fragmentary sectional view showing a modified form of construction of the servo operating mechanism.

My invention is illustrated in the drawing as embodied in a construction having a backing plate 9, a brake drum 10, provided with suitable lining 12, and wherein are arranged brake shoes 14, 16, and 18, adapted to be moved into frictional braking engagement with the drum. These shoes carry suitable brake lining 20. Shoes 16 and 18 are mounted upon a fixed pivot 22 and shoe 14 is pivotally articulated at 24 with shoe 16. Adjustable eccentric devices 26 are provided to determine the idle position of the shoes 16 and 18. A spring 28 holds the shoe 16 against the eccentric 26, and spring 30 holds the shoes 14 and 18 inwardly away from the drum and toward the operating cam.

The shoe 14 is provided with an elongated circumferential opening 32 wherein is arranged a servo shoe 34 one end of which is pivotally connected by a link 36 with a cam 38, which cam is interposed between the adjacent ends of the shoes 14 and 18 to spread them apart against the drum. The cam is shown as provided with projecting ears 39 between which the end of the link is received and pivotally articulated by a pin 40, and the end of the shoe 34 is shown as provided with projecting ears 42 between which the opposite end of the link is disposed and pivotally articulated by a pin 44. In Fig. 2 a spring member 46 is shown as arranged upon the pin or bolt 44 and tensioned by a nut 48 so that the connection between the servo shoe and the link is an adjustable frictional connection whereby the angularity of the link and shoe may be adjustably varied.

The shoe 34 has its opposite end held away from the drum by a spring 50 and the shoe itself is moved into engagement with the drum by a cam 52 carried by a shaft 54. The shoe 14 is of channel shape so that the shoe 34 is arranged therein and the shaft 54 of the op-

erating cam is suitably supported in the backing plate.

The cam 38 is pivotally supported upon a link 56 pivoted at 58 to the backing plate and provided with an angular portion 60 terminating in a pintle 62 upon which the cam is journalled. A key 64 is shown to hold the cam in place. The cam is provided with side flanges 66 which engage upon opposite sides 10 of the reduced end portions 68 of the shoes 14 and 18 thereby holding the shoes in alignment. These reduced end portions 68 take the thrust of the cam in spreading the shoes apart.

15 In Fig. 3 I have illustrated a slightly modified type of construction wherein the idle position of the shoe 34 is determined in part by an adjustable eccentric 70 which extends through and is mounted in the backing plate 20 and which engages the inner face of the shoe 34 adjacent its free end. The spring 50 in this construction is connected to the shoe 34 between the eccentric 70 and the operating cam 52. Otherwise the mounting of the shoe 25 is similar to that shown in Fig. 1. The shoe 14 is, of course, cut away to accommodate for the link 36 as it would be necessary to insure its operation.

In the operation of the device the servo 30 shoe 34 is moved into engagement with the drum by the cam 52 and, rotating with the drum, actuates the cam 38 to spread the ends of shoes 14 and 18 into engagement with the drum. Shoe 14 in turn actuates shoe 16 and 35 the device responds to rotation of the drum in either direction and the mounting of the cam 38 is such that it accommodates itself to such operation or to wear of parts.

The connection between the link 36 and the 40 servo shoe 34 is of such a character that the shoe has a tendency to swing about the pivot 40 so that in the construction shown in Fig. 1 the pivoted end of the shoe will not drag upon the drum. It may also be mentioned 45 that the spring 50 is a relatively weak spring insufficient to overcome the frictional engagement of the shoe with the link. In Fig. 3 there is, of course, no tendency for the pivoted end of the shoe 34 to drag upon the drum 50 when the shoe is in the idle position because spring 50 is connected with the shoe between the eccentric 70 and the cam 52.

This application is a continuation in part of application, Serial No. 149,615, filed November 20, 1926.

What I claim is:

1. In brake mechanism, a brake drum, a pair of brake shoes arranged within the drum to exert a braking force thereon, a servo shoe 60 arranged within one of said brake shoes, means for moving the servo shoe into engagement with the drum, and means coupling the servo shoe with the brake shoes whereby the servo shoe urges the brake shoes against the drum.

2. In brake mechanism, a brake drum, a pair of brake shoes arranged within the drum to exert a braking force thereon, a servo shoe arranged within one of the brake shoes, means for moving said servo shoe into engagement with the drum, and means coupling the servo shoe with the shoe within which it is arranged to force said last named shoe against the drum as the servo shoe is rotatably actuated thereby. 70

3. In brake mechanism, a brake drum, a pair of brake shoes arranged within the drum to be moved thereagainst, a servo shoe arranged within one of said shoes and coupled with the other shoe to urge it against the drum upon actuation of the servo shoe by the drum, and means for moving said servo shoe into engagement with the drum. 80

4. In brake mechanism, a brake drum, a pair of brake shoes arranged within the drum to be moved thereagainst, a servo shoe arranged within one of said shoes and coupled with both of them to urge them against the drum upon rotatable actuation of the servo shoe by the drum, and means for moving said servo shoe into engagement with the drum. 85

5. In brake mechanism, a brake drum, a plurality of brake shoes arranged within the drum, a servo shoe arranged within one of said shoes, means operable to move the servo shoe into engagement with the drum, and means coupling the servo shoe with one of the plurality of brake shoes to urge it into engagement with the drum. 95

6. In brake mechanism, a brake drum, a plurality of brake shoes arranged within the drum, one of said shoes provided with an elongate opening, a servo shoe within said opening, and coupled with one of the brake shoes to urge the same into engagement with the drum. 100

7. In brake mechanism, a brake drum, a brake shoe adapted to exert a braking force thereon, a servo shoe arranged wholly within said shoe and adapted to be moved into engagement with the drum, said servo shoe coupled with the first mentioned shoe to urge the same into engagement with the drum as the servo shoe is actuated thereby. 110

8. In brake mechanism, a brake drum, a brake shoe arranged to exert a braking force thereon, said shoe provided with a circumferential opening, a servo shoe arranged within said opening, a cam to move the servo shoe into engagement with the drum, and a cam coupled with the servo shoe to be actuated thereby to urge said first mentioned shoe into engagement with the drum. 115

9. In brake mechanism, a brake drum, a pair of brake shoes arranged therein to be moved into braking engagement therewith, a servo shoe arranged within one of the brake shoes, means for moving the servo shoe into engagement with the drum, a cam arranged to actuate both brake shoes, and means 120

coupling the cam with the servo shoe to be actuated thereby to urge the brake shoes into engagement with the drum.

10. In brake mechanism, a brake drum, a plurality of brake shoes arranged to be moved thereagainst to exert a braking force thereon, a servo shoe arranged within one brake shoe, means operable to move the servo shoe into engagement with the drum, a cam arranged to urge two of the brake shoes into engagement with the drum, and means coupling the cam with the servo shoe whereby the cam is actuated to urge said two shoes against the drum.

15. 11. Brake mechanism comprising, in combination, a brake drum, a brake shoe operable to engage the drum, a servo shoe arranged within the brake shoe and adapted to be moved against the drum, said servo shoe connected with the brake shoe to urge it against the drum in either direction of travel of the servo shoe with the drum.

12. Brake mechanism comprising, in combination, a brake drum, a plurality of brake shoes arranged within the drum, a servo shoe of less length than any one of said plurality of shoes and arranged within one of them and adapted to be moved into engagement with the drum and means connecting the servo shoe with said plurality of shoes to apply them to the drum.

13. Brake mechanism comprising, in combination, a brake drum, an expansible friction device within the drum having separable ends adapted to be spread apart to apply said friction device to the drum, a servo shoe arranged within said friction device and being of substantially less length and adapted to be urged against the drum and coupled with the separable ends of said friction device to expand it against the drum.

14. Brake mechanism comprising, in combination, a brake drum, a brake shoe arranged therein to be moved against the drum, a servo shoe arranged within the brake shoe to be moved against the drum, and power multiplying means connecting the servo shoe with the brake shoe to apply it to the drum.

15. In brake mechanism, a brake drum, a pair of articulated brake shoes anchored at one end within the drum, a servo shoe arranged within one of the brake shoes to be moved into engagement with the drum and coupled with the floating shoe of said pair of shoes to urge both of them against the drum.

16. Brake mechanism comprising, in combination, a brake drum, a retarding device adapted to be moved into engagement with the drum, a servo shoe pivotally supported to be swung into engagement with the drum and adjustable angularly with respect to its support to vary the arc of its normal position with respect to the drum, means operable to move said servo shoe into engagement

with the drum, and means disconnectedly coupling the servo shoe with the retarding device to actuate it into engagement with the drum.

17. Brake mechanism comprising, in combination, a brake drum, a brake shoe arranged to be moved into engagement therewith, a servo shoe arranged within the brake shoe and pivotally supported at one end for movement into engagement with the drum, a spring constraining the opposite end of the servo shoe away from the drum, a part arranged between the pivoted end and the spring constrained end of the shoe to determine its retracted position with respect to the drum.

18. Brake mechanism comprising, in combination, a brake drum, a brake shoe arranged to be moved into engagement therewith, a servo shoe arranged within the brake shoe and pivotally supported at one end for movement into engagement with the drum, a part arranged in proximity to the opposite end of the servo shoe to determine its retracted position with respect to the drum and adjustable to vary said position, a spring engaging said shoe between said pivoted end and said part constraining the shoe away from the drum.

19. In brake mechanism, a brake drum, a pair of brake shoes arranged within the drum to exert a braking force thereon, a servo shoe arranged within one of said brake shoes, means for moving the servo shoe radially into engagement with the drum, and means coupling the servo shoe with the brake shoes whereby the servo shoe urges the brake shoes against the drum.

20. In brake mechanism, a brake drum, a brake shoe adapted to exert a braking force thereon, said brake shoe provided with an opening therethrough, a servo shoe arranged within said opening, means for actuating said servo shoe into engagement with the drum, and means coupling the servo shoe with the first mentioned shoe to urge the same into engagement with the drum as the servo shoe is actuated thereby.

21. In brake mechanism, a brake drum, a brake shoe arranged to exert a braking force thereon, said shoe provided with a circumferential opening, a servo shoe arranged within said opening, a cam to move the servo shoe into engagement with the drum, and a second cam coupled with the servo shoe to be actuated thereby to engage the end of the first mentioned shoe to urge it against the drum.

22. In brake mechanism, a brake drum, a plurality of brake shoes arranged to be moved thereagainst to exert a braking force thereon, one of said shoes provided with an elongate opening, a servo shoe arranged within said opening, a cam operable to move the servo shoe against the drum, a second cam positioned between the separated ends of two of

the brake shoes, and a link connecting the servo shoe with the second cam to actuate the cam to urge said two shoes against the drum.

23. In brake mechanism, a brake drum, a plurality of brake shoes having separated ends arranged within the drum, one of said shoes provided with an aperture arranged in proximity to said separated ends, a servo shoe arranged within said aperture, a cam operable to move the servo shoe into engagement with the drum, a second cam disposed between the separated ends of said shoes, and means connecting the servo shoe with the second cam to actuate the same to urge the shoes against the drum.

24. In brake mechanism, a brake drum, three pivotally articulated segmental shoes, one being a floating shoe and substantially shorter than the remaining two shoes and having an end portion separated from an end of one of the other shoes, said floating shoe having an elongate circumferential opening, a servo shoe positioned within said opening to engage the drum, means for actuating the servo shoe into engagement with the drum, a cam positioned between the floating shoe and a shoe adjacent thereto, and means connecting said cam with the servo shoe whereby upon rotatable actuation thereof with the drum the cam is actuated to move the shoes engaged thereby against the drum.

25. Brake mechanism comprising, in combination, a brake drum, retarding means arranged within the drum to be moved into engagement therewith, a servo shoe having an arcuate length of less than 90° arranged within the retarding means and adapted to be moved into engagement with the drum and connected with the retarding means to urge it against the drum as the servo shoe is actuated by the drum.

26. Brake mechanism comprising, in combination, a brake drum, a retarding device adapted to be moved into engagement with the drum, a servo shoe arranged within said retarding device and adapted to be moved into engagement with the drum and connected with said retarding device to move it into engagement with the drum in either direction of rotation of the drum.

27. Brake mechanism comprising, in combination, a brake drum, brake shoes having separable ends arranged within the drum to be moved thereagainst, a cam between said separable ends to expand the shoes against the drum, a servo shoe arranged within one of the shoes to be moved against the drum, a link pivotally connecting the servo shoe with the cam to actuate it to urge the brake shoes against the drum in either direction of rotation of the drum.

28. Brake mechanism comprising, in combination, a brake drum, a brake shoe arranged therein to be moved against the drum, a servo shoe pivotally supported within the brake

shoe to be urged against the drum, said servo shoe connected with the brake shoe to apply it to the drum.

29. Brake mechanism comprising, in combination, a brake drum, a retarding device adapted to be moved into engagement therewith, a servo shoe, angularly adjustable means supporting the servo shoe for swinging movement into engagement with the drum, means operable to move the servo shoe into engagement with the drum, and means actuated by the servo shoe disconnectedly coupled with the retarding device to urge the same into engagement with the drum.

30. Brake mechanism comprising, in combination, a brake drum, a retarding device adapted to be moved into engagement with the drum, a servo shoe, means supporting the servo shoe for swinging movement into engagement with the drum automatically adjustable to vary the normal position of the servo shoe with respect to the drum, means operable to apply the servo shoe to the drum, and means disconnectedly coupling the servo shoe with the retarding device to apply it to the drum.

31. Brake mechanism comprising, in combination, a brake drum, expansible retarding means arranged therein and having spaced apart ends, and applying mechanism including a servo shoe, a pivotally supported link, a cam pivotally supported upon the link between the ends of said retarding means and an operating connection between the servo shoe and that end of the cam adjacent to the periphery of the drum.

32. Brake mechanism comprising, in combination, a brake drum, a friction member supported therein, a servo shoe therein, a rock member supporting the servo shoe for movement into engagement with the drum, said rock member being automatically angularly adjustable with respect to the shoe to take up for wear of the shoe, and means supporting the rock member for actuating the friction member.

In testimony whereof, I, ROY S. SANFORD, sign this specification.

ROY SELDEN SANFORD.
